WINDOW CONSTRUCTION

Filed July 14, 1930

Inventor:
Ernest J. Liebmann
by Wallace R. Elmer.
J. E. L.

UNITED STATES PATENT OFFICE

ERNEST J. LIEBETRAU, OF NILES, MICHIGAN, ASSIGNOR TO THE KAWNEER COMPANY,
OF NILES, MICHIGAN, A CORPORATION OF MICHIGAN

WINDOW CONSTRUCTION

Application filed July 14, 1930. Serial No. 467,771.

The present invention relates to window constructions, and more in particular to a window having a slidable sash and a transom therein, the same being mounted in a frame, whereby the frame, slidable sash and transom are assembled as a unit at the factory, and adapted to be mounted as such unit in a structure, such as a ship, etc.

Among the objects of the present invention 10 are to provide a window construction having an upwardly opening, slidable sash therein, and a transom mounted thereabove and adapted to swing outwardly therefrom.

A further object is to provide a novel 15 metallic sash construction adapted to make a weather-tight closure with a meeting rail of the frame. The invention comprehends the provision of a slidable sash adapted to be raised into a well formed in the upper portion 20 of the window frame, and when in such raised position, said sash is mounted alongside of the transom.

A still further object is the provision of a 25 novel window frame construction adapted to be assembled with the sash and transom, at the factory, and the entire assembly unit adapted to be placed in an opening in the hull of a ship, and there mounted in position, the outside of the frame being suitably connected to the metal plate of the ship. By 30 constructing the frame, sash and transom of metal, the invention saves considerable in the cost of constructing, assembly and maintenance of windows, and provides a more 35 rigid construction which admirably fills the need so long felt in ship construction.

Another object of the invention is the provision 40 of a sash construction in which the top rail thereof is removable in order to facilitate glazing of the same. Further objects are to provide a construction of maximum simplicity, efficiency, economy and ease of assembly, detachment and maintenance, and such 45 further objects, advantages, and capabilities

as will later more fully appear, and are inherently possessed thereby.

The invention further resides in the combination, construction, and arrangements of parts illustrated in the accompanying drawing, and while there is shown therein a preferred embodiment, it is to be understood that the same is susceptible of modification and change, and comprehends others details, arrangements of parts, features and constructions, without departing from the spirit of the invention.

Referring to the drawing:

Fig. 1 is an exterior view in side elevation of the novel window construction.

Fig. 2 is a view in vertical cross section taken in a plane represented by the line 2—2 of Fig. 1.

Fig. 3 is a fragmentary view in horizontal cross section taken in a plane represented by the line 3—3 of Fig. 1.

Fig. 4 is a fragmentary view in horizontal cross section taken in a plane represented by the line 4—4 of Fig. 1.

Fig. 5 is a fragmentary view in side elevation of an upper edge of the sash construction.

Referring more particularly to the disclosure in the drawing, the numeral 1 refers to the hull or metal plate of the ship structure, 70 although it is to be understood that the present invention, while being particularly adapted for use in ship construction, is admirably adapted to be used in other structures, such as buildings or the like. The hull or metal plate of the ship is shown as provided with an opening 2 for the reception of the window frame 3, provided with the slid- 75 able sash 4 and transom 5. The frame 3 includes a sill 6, head jamb 7, and side members 8 and 9. The sill 6 is shown as having its interior portion 10 seated upon a stool 11, and its exterior portion 12 connected to a metal trim 13, as by means of rivets or other suitable connecting means 14.

The stiles 8 and 9 have their interior portion 15 seated against jambs 16, and their outer portion 17, bent upon itself to provide a groove or channel 18 for the reception of the metal trim 19. The numeral 20 refers to a transverse member or wood trim positioned on the interior of the window frame.

The sash 4 is disclosed as including a bottom rail 21, side rails 22, and a top rail 23. 10 The bottom and side rails are disclosed as of a similar construction, and may be connected together by any suitable means such as welding, or by other attaching means, and are formed to provide channel members 24 having a downwardly or outwardly extending doubled-over portion 25. On the side rails, this doubled-over portion 25 is adapted to be received in longitudinally extending grooves or channels 26 so as to form a weather-tight 15 closure. The doubled-over portion 25 of the lower rail 21 is adapted to abut against a shoulder 27, while a portion of the channel member seats in a shouldered portion 28 on the sill 6, so as to form a weather-tight closure 20 therewith when the sash is in its lowered, closed position. The top rail 23 is provided with a channel member 29 and an outwardly and downwardly extending doubled-over portion 30.

25 The transom 5 is swingably connected at its upper end to a head plate 31 by means of hinges or the like 32, these hinges being connected to the head plate, and to the top rail 33 of the transom. The top rail 33, bottom rail 34, and side rails 35 of the transom are of similar construction, and include a channel member 36 provided with an inwardly extending doubled-over portion 37.

30 The doubled-over portion 37 on the side rails 35 are adapted to be received, when in closed position, in L-channel members 38, while the doubled-over portion on the top rail 33 is adapted to be received in the horizontally extending groove or channel 39 45 formed in the head plate 31.

In order that the doubled-over portion of the bottom rail 34 of the transom, and the doubled-over portion 30 of the top rail of the sash, may form a weather-tight closure 50 when in closed position, there is provided a meeting rail 40. This meeting rail comprises a plate or sheet of metal bent upon itself to form an outwardly opening groove or channel 41 adapted to receive the doubled-over portion 37 on the bottom rail 34 of the transom, a central member 42 and a channel member 43 adapted to receive the doubled-over portion 30 of the sash 4. This meeting rail 40 is connected by any suitable means to the stiles 8 and 9, as by welding, brazing or the like.

55 As disclosed in Figs. 1 and 2, the window frame is provided with a well 44 in its upper portion for the reception of the sash 4 when in open position. The transom 5 may be op-

erated by any suitable mechanism (not shown) for opening and closing the same. Suitable catch members 45 are mounted on opposite sides of the sash near the bottom thereof, and are each provided with a plunger 70 adapted to seat within openings in the stiles 8 and 9, so that the sash may have various positions of adjustment.

In order to strengthen the sash and transom rail construction, the bottom rail 21 and side rail 22 of the sash member, and the top rail 33 and side rails 35 of the transom member, are each provided with a reinforcing bar 46. In order to permit ready glazing of the sash, the top rail 23 thereof and the side rail 22 are cut on a bias as at 47 to permit the ready removal of the top rail. When the glass is in position, the top rail 23 is applied, and counter-sunk screws or bolts are applied at each side of the top rail, these screws or bolts passing through the top rail, and into the reinforcing bars 46 in the side rails, these reinforcing bars being interiorly threaded to receive the same.

55 The glass 49 in the sash 4 and the glass 50 in the transom 5, are shown as seated in felt or the like 51, while suitable weather stripping 52 is embedded in the grooves or channels of the meeting rail 40, and in the channels formed in the channel members of the transom, so that a weather-tight closure is made whenever the transom and sash are in closed position.

60 The assembled window unit, when placed in the opening formed in the hull of the ship, is connected to the hull or metal plate 1 by means of bolts, rivets or the like 53, whereby a weather-tight and water-proof assembly is formed. Although the invention has been disclosed as applicable to the hull of a ship, 65 it is of course to be understood that the same is adapted for numerous uses and can be assembled in numerous structures wherever such an assembly is desired.

Having thus disclosed my invention, I claim:

1. In a window construction, a frame, a sash slidable vertically in said frame, a transom swingably mounted above said sash, and a meeting rail adapted to receive a portion of said sash and transom when in closed position to provide a weather-tight seal therebetween.

2. In a window construction, a frame, a sash slidable in said frame, a transom swingably mounted above said sash, a well in the upper part of said frame for receiving the entire sash when the same is in open position, and means for locking said sash in various positions of elevated adjustment.

3. In a window construction, a frame, a sash slidable in said frame, a transom swingably mounted above said sash, a well extending from adjacent said transom to above the same for receiving the entire sash when the

same is in open position, and means for locking said sash in various positions of elevated adjustment.

4. In a window construction, a frame, a sash slideable in said frame, catch means for holding said sash in various positions of adjustment, a transom swingably mounted above said sash, and a meeting rail adapted to receive a portion of said sash and transom when in closed position to provide a weather-tight seal therebetween.

5. A unitary metallic window construction for a ship, comprising a frame adapted to be mounted in an opening in the hull of the ship, a sash slideable vertically in the frame, a transom swingable in said frame, and a meeting rail for receiving an edge of said sash and transom when they are in closed position.

20 6. A unitary metallic window construction for a ship, comprising a frame adapted to be mounted in an opening in the hull of the ship, a sash slideable in the frame, a transom swingable in said frame, said sash and transom having sides, top, and bottom rails formed of metal plate bent upon itself to provide rib portions, and means in said frame for receiving said rib portions when the sash and transom are in closed position 30 in order to form a weather tight seal.

7. A unitary metallic window construction for a ship, comprising a frame adapted to be mounted in an opening in the hull of the ship, a sash slideable in the frame, a transom swingable in said frame, said sash and transom having sides, top and bottom rails formed of metal plate bent upon itself to provide rib portions, means in said frame for receiving said rib portions when the 40 sash and transom are in closed position in order to form a weighter-tight seal, the top rail of the sash being removable for facilitating glazing of the sash.

8. In a window construction, a frame, a sash vertically slideable in said frame, a transom swingably mounted above said sash, and a meeting rail adapted to receive adjacent portions of said sash and transom when in closed position whereby to provide a 50 weather-tight seal.

9. In a window construction, a frame, a sash vertically slideable in said frame, a transom swingably mounted above said sash, and a bar adapted to receive adjacent portions 55 of said sash and transom when in lowered position to provide a weather-tight seal.

10. A unitary metallic window construction for a ship, comprising a frame adapted to be mounted in an opening in a ship, a sash vertically slideable in the frame, a transom swingable in the frame, said sash and transom being provided with projecting portions adapted to form a weather-tight seal with the frame when the same are in 65 closed position.

11. A unitary metallic window construction for a ship, comprising a frame adapted to be mounted in an opening in a ship, and provided with a meeting rail, a sash vertically slideable in the frame, and a transom 70 swingable in the frame, adjacent ends of said sash and transom engaging said rail when in closed position whereby to provide a weather-tight seal therewith.

In witness whereof, I hereunto subscribe 75 my name to this specification.

ERNEST J. LIEBETRAU.
